(57) **CLAIM**

The ornamental design for a spreader, as shown and described.

DESCRIPTION

FIG. 1 is a top front perspective view of a spreader showing my new design;

FIG. 2 is a bottom front perspective view thereof;

FIG. 3 is a top rear perspective view thereof;

FIG. 4 is a bottom rear perspective view thereof;

FIG. 5 is a front elevation view thereof;

FIG. 6 is a right elevation view thereof;

FIG. 7 is a left elevation view thereof;

FIG. 8 is a rear elevation view thereof;

FIG. 9 is a top plan view thereof; and,

FIG. 10 is a bottom plan view thereof.

In the drawings, the broken lines depict portions of the spreader that form no part of the claimed design.
